MUSIC STAND

Filed Aug. 28, 1937

FIG. 1.

FIG. 2.

UNITED STATES PATENT OFFICE

2,236,610

MUSIC STAND

Sydney Skamser, Los Angeles, Calif.

Application August 28, 1937, Serial No. 161,445

8 Claims. (Cl. 45—121)

My invention relates to music stands and has particular reference to a music stand which may be folded into a relatively flat compact package adapted to be carried in an ordinary music instrument case.

Musicians who usually perform at established locations have more or less permanent music stands provided at these locations but the occasion frequently arises when either an additional stand is needed or the musician is required to play at other locations, making it necessary for him to carry a folding or collapsible music stand. Present types of music stands of the folding or collapsible types are rather bulky, even when folded, making it impossible to place these stands in the case of an ordinary musical instrument such as violin, cello and the like, and requiring that the musician carry with him from place to place a package holding the music stand in addition to carrying his instrument and its case.

It is an object of my invention to provide a music stand which may be so folded as to be completely contained within a flat shallow tubular standard, which standard constitutes a carrying case which may be readily located within the ordinary violin, cello or similar instrument case, either placed loosely therein or placed into a counter-sunk depression formed in the interior of the case.

Another object of my invention is to provide a music stand of the character set forth wherein in the standard or post of the music stand may be constructed of a pair of telescopically assembled metal tubes, preferably having a rectangular lateral cross section, one axis of which is relatively short and the other axis of which is relatively long, producing a flat tubular case which will occupy comparatively little space in an instrument case.

Another object of my invention is to provide a music stand of the character set forth wherein in a music holding rack is provided, capable of being folded into such small compass as to allow it to be inserted in and to be received within the interior of the innermost of the telescopically assembled tubes, and in which the music supporting shelf comprises a substantially inflexible single piece construction.

Another object of my invention is to provide a music stand of the character set forth in the preceding paragraph wherein the music supporting shelf may be unfolded and attached to the upper end of the standard by means of a relatively rigid supporting member which acts both

to hold the music shelf and arms for supporting the music in outspread position.

Another object of my invention is to provide a music stand of the character set forth wherein in the music rack may be attached to the upper end of the standard in either a sharp angle to the vertical for ordinary playing or more nearly horizontal for use in directing.

Another object of my invention is to provide a music stand of the character set forth wherein foldable foot members are provided adapted to be permanently telescopically assembled within the lower end of the standard and which, when drawn outwardly therefrom, comprises a fixed height base or foot supporting the standard in a vertical position.

Other objects and advantages of my invention will be apparent from a study of the following specifications, read in connection with the accompanying drawing, wherein,

Fig. 1 is a perspective view of my music stand in closed or folded position ready for insertion in an instrument case;

Fig. 2 is a perspective view of my music stand in its unfolded position ready to receive and support music sheets;

Fig. 3 is a detail vertical sectional view taken through the music stand in its unfolded position;

Fig. 4 is a detail perspective view of the music supporting rack in unfolded or playing position; and

Fig. 5 is a plan view of the music rack in folded position ready for insertion into the upper end of the standard tubes.

Referring to the drawing, I have illustrated in Fig. 1 the music stand constructed in accordance with my invention as being in folded or closed position, the music stand comprising a pair of telescopically assembled tubes 1 and 2, which together constitute the standard or upright post for supporting a music rack 3 at any desired level above the floor or other surface upon which the stand may be placed. In Fig. 2 the music stand is illustrated in its unfolded position ready for receiving music, the tubular members 1 and 2 having been drawn outwardly relative to each other to extended position. As is illustrated in this figure, the inner tube 2 may have a plurality of small holes 4 punched, cut or drilled into one side wall of the tube, into which may be received the end of a lock pin 5 preferably secured to the upper end of a short spring strip 6, which is in turn secured at or

50

near its lower end to the corresponding side of the outer tube 1.

As illustrated herein, the tubular members 1 and 2 are preferably elongated sections of metal tube, preferably selected of such material as to be relatively light in weight though having the characteristic of being substantially inflexible so as to provide a substantially rigid post for supporting considerable quantities and weights of music without distortion. I prefer to select 10 tubes having substantially rectangular lateral cross sections in which the minor axis is relatively short as compared with the major axis so that the tubular members may be received in a relatively shallow space within the instrument cases; for example, in a violin case, as distinguished from present constructions of music stands which have substantially bulky lateral cross sections, rendering it impossible to place them within the ordinary instrument case. For 20 example, I prefer to select as the outer tube 1 a tubular member having a lateral cross section, the minor axis of which is approximately $\frac{1}{2}$ inch while the major axis may range from 1 inch to $1\frac{1}{2}$ inches, so that when contained within an instrument case it will occupy a shallow space only $\frac{1}{2}$ inch deep. The inner tube 2 is selected of lateral cross sectional dimensions just permitting the same to be received within the interior of the tube 1 to make a sliding fit therewith and to permit the tube 2 to be telescoped therein from its extended position as shown in Figs. 2 and 3, to its contracted position as shown in Fig. 1.

The lower end of the tube 1 has received there- 35 in a foot member 7 which preferably comprises a short rectangular block 8, the external dimensions of which are equal to the internal dimensions of the tube 2 so that this block 8 may be pressed upwardly through the tube 1 and into the lower end of the tube 2 when tubes 1 and 2 are in their contracted position. The upper 40 end of the block 8 is preferably provided with a beveled or tapered portion 9 which assists in guiding the block 8 into the lower end of the tube 2 and has attached thereto one or more flat spring members 10 adapted to engage the upper edge of a lining 11 set into the bottom end of the tube 1. The lining 11 is preferably selected of material of the same thickness as that from which the tube 2 is made so that when the lining 11 is in place within the tube 1 it defines a vertically extending opening having the same lateral dimensions as the interior of the tube 2 so that it receives and snugly fits the block 8, making a coupling therewith substantially rigid in lateral directions.

The lower end of the block 8 is provided with a plurality of recesses 12, one on each of the four sides of the block 8, and into each of which may be received the inner end 13 of leg members 14 where the same may be retained by means of pins or rivets 15. This connection of the leg members 14 to the block 8 allows the leg members to be spread to the position shown in Fig. 2 or to be collapsed or folded toward each other to a compass which readily permits them to be received within the lower end of the tube 1 when the plug 8 is moved upwardly therein.

It will be noted that the lower end of the tube 1 is provided with a plurality of notches 16 adapted to receive the legs 14 when they are moved outwardly to their extended positions and, while their reception in these notches may be

sufficient to lend rigidity to the foot member and standard, I prefer to interconnect each pair of opposed legs 14 by means of toggle links 17 and 18 and having friction washers 17a, 18a at their junction, so that when the legs are moved outwardly to the position shown in Fig. 3 the toggle links and washers act to hold the legs 14 in their extended positions.

It will be noted that the foot member 7 is thus permanently secured to the standard formed by tubes 1 and 2 and, while it may be moved inwardly and outwardly relative to the tubes from a completely enclosed position as shown in Fig. 1 to its extended position as shown in Fig. 2, the foot member 7 never becomes detached from the standard. If desired, a small leather, cloth or other loop 19 may be provided upon one of the legs 14 which will extend outwardly of the lower end of the tube 1 when the foot member 7 has been folded and telescoped therein to constitute a handle by which the foot member 7 may be drawn outwardly to its extended position.

The upper end of the tubular member 2 is 25 preferably thickened as indicated at 20 so as to provide a shoulder 21 adapted to come to rest upon the upper end of the tube 1 when tubes 1 and 2 are in their collapsed or telescoped positions as shown in Fig. 1. Also the strengthening or thickening of the walls of the tube 2 near its upper end assists in forming a head at the upper end of tube 2 which may act as one part of a detachable connection between the standard and the music supporting rack 3.

By referring particularly to Fig. 4, it will be noted that the music rack 3 comprises a music supporting shelf member 22 preferably constructed of a short length of metal having a right angle cross section. The thickness of the material constituting the shelf 22 is not material so long as it is sufficient to support the weight of a considerable quantity of music without undue flexing and without collapse. The shelf member 22 is preferably constructed so that its center 23 is at a slightly lower level than its outer ends 24 and 25 so that by providing a substantially wedge-shaped filler 26 at the center 23 music resting upon the shelf member 22 will be held with a 3-point support, namely, the shelf 22 will engage the music at its center (usually the fold) and at each of the outer ends, while the remaining portions of the lower edges of the music sheet, book or other device will be free of contact with the shelf 22. By providing this construction it will be apparent that the leaves or pages of music may be readily turned without dragging or scraping upon the shelf 22.

The shelf member 22 has attached thereto a plurality of music supporting arms, preferably 60 two, indicated herein at 27 and 28, each of which may be constructed of a short length of relatively narrow metal bar elements, one end of each of which is pivoted as indicated at 29 and 30 to opposite ends of the shelf member 22. Each 65 of the arms 27 and 28 is preferably selected of a length just slightly shorter than the length of the shelf member 22 so that these arms may be folded down upon the shelf member 22 to the position shown in Fig. 5, the arm 27 being preferably spaced from the rear angle 31 of the shelf member 22 by means of a spacer 33 so that arm 28 may be folded down at the rear of arm 27. The two arms 27-28 are interconnected with each other by means of a sliding sleeve 34 which 70 may be pivotally secured to the arm 28 and ex-

tend about the arm 27 so that when one of the arms 28 is lifted or unfolded the other arm 27 will also be lifted or unfolded to dispose both arms 27 and 28 at substantially the same angle to the shelf 22.

To limit the outward movement of the arms relative to the shelf 22, I prefer to provide a recess or slot 35 in that portion of the arm 27 along which the slide 34 travels, the ends of the notch or slot 35 constituting shoulders 36 acting as abutments or stops limiting the spreading or unfolding of the arms.

To hold the shelf 22 and arms 27-28 in their extended or unfolded positions and to constitute an attaching means for coupling the music holding rack to the standard 1-2, I employ a support 37, which may be constructed of a short length of metal bar having a substantially rectangular cross section, one edge of which is slightly less than the narrow width of the tubular member 2 while the other edge of which is slightly less than the longer width of the tube 2. The lower end of the support 37 is provided with a notch 38 extending from its front face, the notch constituting a recess into which the rear angle 31 of the shelf 22 may project, the notch 38 being sufficiently deep to allow at least a portion of the shelf 22 to be recessed within and lie below the front surface of the support 37. A short tongue 39 projects downwardly into the recess or notch 38 so as to engage in front of the flange 31 when the shelf member 22 is inserted in the notch. Spaced along the support 37 is a second notch 40 approximately as deep as the assembled thickness of the arms 27-28, the notch 40 having a longitudinally extending portion 41 adapted to snugly engage and form a seat for the arm 28. The location of the notch 40 is such that when the arms are unfolded to their limit, as shown in Fig. 4, the arm 28 may be received in the notch 40 and will hold the arms 27-28 in their extreme unfolded position. It will be noted that by the 2-point attachment of the support 37, namely, at the notches 38 and 40, a rigid bracing and support is provided for the shelf 22 and its associated arms 27-28 while the upper end of the support 37 constitutes a central brace or bracket against which the central portion or hinge of music sheets lying upon the shelf 22 may be additionally supported.

The support 37 is provided with a slot 42 extending from its rear surface, of such dimensions as to allow the front wall of the upper end of tube 2 to be received therein, the upper end of tube 2 being provided with a slot 43 (see Figs. 1 and 2), permitting the support 37 to nest therein, the engagement of the upper end of tube 1 with the support 30 detachably fixing the support to the tube. It will be noted that the slot 42 extends at a considerable angle to the longitudinal axis of the support 37 so that when the support is assembled with the standard in the positions shown in full lines in Fig. 3, the music supporting rack will extend at a considerable angle to the horizontal, namely, in an appropriate position to permit ready reading of the music when the player is seated.

However, to adapt my music rack to be readily used by a director, I provide a pair of additional slots 44 and 45 on each side of the support 37, these slots being spaced from each other longitudinally of the support 37 a distance equal to the spacing of the front and rear walls of the tube 20 and having such dimensions as will allow the upper end 20 of the tube 2 to be nested

or received therein in the position shown in dotted lines in Fig. 3, disposing the music supporting rack at a more nearly horizontal position.

5 When the device is to be transported, all of the parts may be folded and telescopically assembled as shown in Fig. 1 to provide a package, the dimensions of which are only the length of the tubular member 1 and having a cross sectional dimension equal to the cross sectional dimension of the tube 1. When the device is to be folded, the foot member 7 may have its legs 14 folded down toward each other and the entire assembly may then be pressed inwardly of the tube 1, remaining in this position by the frictional contact between the block 8 and the tubes 1 and 2. The tube 2 may then be telescopically contracted into the tube 1 until its enlarged head 20 rests upon the upper end of the tube 1. 10 The music supporting rack may be lifted off of the upper end of tube 1, the shelf 22 being given a slight rotary twist in a counterclockwise direction, as viewed in Fig. 3, releasing the shelf 22 from the notch 38 and then the arms 27-28 may be lifted out of the notch 40. The arms 27-28 may then be folded down to the positions shown in Fig. 5 and the support 37 laid upon the shelf 22 in the position shown in Fig. 5.

It will be noted that the support 37 has a shallow recess 46 in one or both of its side faces, sufficiently deep to receive the wedge block 26 therein and allow the support 37 to nest flatly upon the shelf 22. When the music rack has been folded into this position, it may be inserted 30 into the upper end of tube 2 and pressed downwardly therein to the position shown in Fig. 1, the entire assembly being then ready to be placed in any shallow space, recess or other portion of an instrument carrying case.

35 The support 37 may also be adapted to carry accessories frequently used by the musician, such as a tuning whistle 47 adapted to be pressed into and frictionally engage with a longitudinally extending bore 48 in the lower end of the support 37. If desired, the tuning whistle 47 may constitute a cap for a mechanical pencil 49 and the entire assembly may be supported in the bore 48 as by providing an extension 48a of the bore sufficiently long in the support 37 to receive the entire pencil and tuner assembly. If desired, the rear wall of the support 37 may be cut away, as indicated at 50, to provide ready access to the pencil 49 and a spring 51 may be set into the recess so formed to frictionally engage the pencil and hold it in place.

55 Likewise, the spacer 33 may be permitted to extend outwardly beyond the end of the shelf 22 to constitute a hook upon which a violin bow or the like may be hung from and supported upon the music stand.

60 In view of the limitation of the length of the arms 27-28 to the length of the shelf 22 so that the arms may be folded thereon, extensions 27a and 28a may be formed upon the respective arms as by providing a cut-out portion 28b into which may be received the extension 28, preferably constructed of material about one-half the thickness of the material of the arms 27-28. The extensions 28 may be pivoted as indicated at 28c to the extreme outer edges of the arms to be moved to the extended position as shown in Fig. 4, or to the folded position as shown in Fig. 4.

65 While I have shown and described the preferred embodiment of my invention, I do not desire to be limited to any of the details of con-

struction shown or described herein, except as defined in the appended claims.

I claim:

1. A music supporting rack comprising a one-piece shelf, a pair of arms, one end of each arm pivoted to an end of said shelf, sliding means intercoupling said arms at points spaced from said pivots, and a detachable support bar having means for detachably engaging said shelf and extending transverse thereto and having means thereon engaging said arms at points spaced from said pivots.

2. A music supporting rack comprising a one-piece shelf, a pair of arms, one end of each arm pivoted to an end of said shelf, a slide pivoted to one of said arms and encircling the other of said arms at points on said arms spaced from said pivots, and a detachable support bar having means for detachably engaging said shelf and extending transverse thereto and having means thereon engaging said arms at points spaced from said pivots.

3. A music supporting rack comprising a one-piece shelf, a pair of arms, one end of each arm pivoted to an end of said shelf, a slide pivoted to one of said arms and encircling the other of said arms at points on said arms spaced from said pivots, an elongated recess in said other of said arms for receiving said slide and forming with said arm abutments limiting the movement of said slide relative to said arm, and a detachable support bar having means for detachably engaging said shelf and extending transverse thereto and having means thereon engaging said arms at points spaced from said pivots.

4. A music supporting rack comprising a one-piece shelf upon which the lower edges of music sheets may rest, the ends of the shelf being positioned at a level above the center thereof and having disposed near its center a block for supporting the central portion of said music sheets at a level above the adjacent portions of said shelf and in alignment with the ends of the shelf to facilitate rapid turning of said sheets.

5. A music supporting rack comprising a one-piece shelf, a pair of arms, one end of each arm pivoted to an end of said shelf, sliding means intercoupling said arms at points spaced from said pivots, and a detachable support bar having means for detachably engaging said shelf and extending transverse thereto and having means thereon engaging said arms at points spaced from said pivots, said bar including a notch near the lower end thereof for receiving said shelf, and a second notch spaced from said lower end for engaging said arms when in unfolded position.

6. A music supporting rack comprising: a pair of arms disposed transversely of each other and interconnected at their intersection; a one-piece shelf upon which the lower edges of music sheets may rest attached to one end of one arm and

extending to the corresponding end of the other arm and attached thereto for holding said ends in spaced relation to each other, the ends of said shelf being disposed at a level above the center of said shelf; and a block disposed near the center of said shelf having an upper surface disposed in substantial alignment with the ends of said shelf for supporting a central portion of said music sheets at a level above the adjacent portions of the shelf to facilitate rapid turning of said sheets.

7. In a foldable music stand of the type including a tubular standard, a foldable music rack and a foldable foot receivable in said standard, the combination of: a foldable music rack including a relatively wide one-piece sheet supporting member, a pair of back forming members secured thereto and being foldable to a position on and closely adjacent to a side edge of said supporting member and a post member adapted to be detachably positioned on said supporting member alongside the back forming members when the latter are in a folded position, said post forming member when in operative position serving to retain the back forming members in distended position above the sheet supporting member; a tubular standard for supporting said rack and for in one end receiving said music rack when folded, said standard having a substantially rectangular cross section, the width of which is from one to one and one-half inches and the depth of which does not exceed one-half the width; and a foldable foot structure receivable when folded in the other end of said standard, whereby said music stand when folded presents a flat cross sectional contour permitting insertion of said folded stand in a violin case within a shallow space not occupied by the violin and without alteration of the case.

8. In a foldable music stand adapted when folded to be received in a violin case within a space not occupied by the violin, the combination of: a tubular standard having a substantially flat rectangular cross section, the dimensions of which do not exceed one and one-half inches by one-half of an inch; a foldable music rack including a relatively wide one-piece sheet supporting member, a pair of back forming members secured thereto and being foldable to a position on and closely adjacent to a side edge of said supporting member and a post member adapted to be detachably positioned on said supporting member alongside the back forming members when the latter are in a folded position, said post forming member when in operative position serving to retain the back forming members in distended position above the sheet supporting member, said rack being foldable into a package receivable in one end of said standard; and a foldable foot receivable in the other end of said standard.

SYDNEY SKAMSER.
